FLUID FUEL BURNING FLOOR FURNACE

James Stanley Johnson, Pasadena, Calif.

Application August 28, 1944, Serial No. 551,557

22 Claims. (Cl. 126—116)

1

My invention relates to heating devices and, more particularly, to a heating unit for installation in the floor of a building. The invention is particularly applicable to floor-installed heating units known in the art as floor furnaces or space heaters; also to other heating devices which may be lowered through the opening of the floor of a building and suspended in the space between the floor and the ground.

In the construction of such floor-installed heating units, it is customary to employ a combustion-chamber structure disposed within an outer casing suspended from the floor and separated from this casing to provide a circulating-air passage. The structure may be such, as in a floor furnace, that air can be withdrawn from the room through the casing-covering grill and circulated in indirect heat exchange relationship with the products of combustion, which products are discharged to a suitable vent, or a part or all of the air may move upward from beneath the floor through the circulating-air passage.

The installation and servicing of floor-installed heating units has always presented a distinct problem as it has required crawling under the building and working in cramped quarters between floor and ground to make connections, adjustments, or repairs. Thus, in conventional structures, the fuel-control means, such as the control valve for the main burner and the pressure regulator, are disposed outside the casing and at a low position, usually at the end of the main burner, to be accessible for connection, inspection, adjustments, or repairs only from underneath the building. Similarly, the pilot construction is also difficultly accessible.

It is an object of the present invention to dispose the fuel-control means at positions accessible from the room to be heated and to provide for connection, adjustment, or repair of any or all of the fuel-control means and the pilot structure by disposing same in a manner to be readily accessible from the open end of the outer casing of the heating unit. It is also an object of the invention to provide a heating unit which can be lowered through the floor opening and which can be connected to the fuel-supply piping without necessitating entry into the usually-limited-height space beneath the building. In this latter connection, it is an object of the invention to provide a heating unit which can be connected to a fuel-supply pipe extending through or adjacent the floor joists. Thus, a stubbed-off fuel-supply pipe may extend a distance into the opening into which the heating unit is to be lowered, and it is

2

an object of the invention to provide a passageway in the heating unit to receive such stubbed-off pipe during lowering of the unit, and to provide a structure in which the stubbed-off pipe is readily accessible for connection to the fuel-control means.

In the preferred forms of the invention, pipes supplying fuel to the main burner and to the pilot extend downwardly inside the outer casing, in accordance with one object of the invention. However, regulations sometimes prohibit the presence of such pipes in a circulating-air passage, and it is an object of the invention to provide a novel enclosure for such pipes, this enclosure preferably also enclosing the fuel-control means and, in accordance with the preferred embodiments, being readily removable.

Other objects of the invention lie particularly in the novel pilot arrangements of the invention. For example, the invention provides for connection or servicing of the pilot from the room being heated and for a pilot which can be withdrawn from the combustion chamber by manual manipulation from the room.

It is conventional practice to mount both the burner and the pilot in an opening in the bottom of the combustion chamber. The invention has among its objects the extension of the pilot through a separate opening of the combustion chamber, usually higher than the lower end of this chamber and usually through a side wall of the combustion chamber; also the provision of a pilot-guiding means facilitating insertion of the pilot into its correct relationship with the combustion chamber and the burner. Also included among the objects is the provision of a pilot extending substantially horizontally into the combustion chamber and preferably mounted so that it can be swung or moved into and from the combustion chamber, usually while moving substantially horizontally.

Other objects and advantages of the invention will be evident to those skilled in the art from the description of the alternative embodiments herein-contained.

Referring to the drawings:

Figure 1 is a vertical sectional view of an installed gas-fired floor furnace;

Figures 2, 3, and 4 are, respectively, sectional views taken on correspondingly numbered lines of Figure 1, Figure 2 showing also a portion of the vent means in section;

Figure 5 is a vertical sectional view, taken along the line 5—5 of Figure 4;

Figure 6 is a fragmentary view in vertical sec-

tion showing an alternative pilot-guiding structure;

Figure 7 is a top view, partially in section, of an alternative pilot construction; and

Figure 8 is a vertical sectional view, taken along the line 8—8 of Figure 7.

Referring particularly to Figures 1 to 5, the exemplified floor furnace includes a generally rectangular outer casing 10 having a bottom wall 11 and of such dimensions as to be inserted in an opening 12 of the floor. The length of the outer casing is such as to occupy the space between two members such as joists 13 supporting rough flooring 14 and finished flooring 15, or the members 13 may be opposed members of a framed-in opening. The outer casing 10 may be suspended in an opening 12 by any conventional means and extends downwardly beneath the floor to occupy a portion of the space above the ground level. The opening 12 is later covered by the usual grill 16.

A combustion-chamber structure 20 is disposed within the outer casing 10 to form a circulating-air passage, indicated generally by the numeral 21, between the outer casing 10 and the exposed surfaces of the combustion-chamber structure 20. It is often desirable to provide a rectangular inner casing 22 as a baffle means in the circulating-air passage 21. As shown, this inner casing 22 is a double-walled structure including inner and outer rectangular baffles 24 and 25 with an air-filled insulating space therebetween open at its top and bottom. It should be understood, however, that a single-walled inner casing can be employed. In operation, cool air drawn from the room moves downwardly in the outer portion of the circulating-air passage 21 between the outer casing 10 and the outer baffle 25, as indicated by arrow 27, flowing thence under and upward within the inner casing 22, as suggested by arrows 28, to be heated by indirect heat transfer from the products of combustion in the combustion-chamber structure 20. If desired, additional air may enter from beneath the floor through an opening 30, shown in Figure 2, but the use of such an opening is optional.

The lowermost end of the combustion-chamber structure 20 is open and is aligned with, and preferably extends snugly into, a rectangular opening 32 of the bottom wall 11. This combustion-chamber structure 20 provides a combustion chamber 33 open at its lower end to receive an elongated burner 35 disposed below or within the open lower end. The products of combustion move upward and through lateral flues 36 to a vertical flue 37, and thence downward to a lateral flue 38 which terminates in or just beyond a recessed portion 39 of the side wall of the outer casing 10, as best shown in Figure 2, to provide a collar 40 adapted to receive a suitable vent connection extending to an upright vent or flue leading to the top of the building. The combustion-chamber structure 20, which may be considered as comprising the combustion chamber and the flues 36 and 37, thus confines the hot products of combustion which, before being withdrawn by the flue 38 traversing the circulating-air passage 21, heat the internal structure to transfer heat to the circulating air.

It is often desirable to mount a pan 45 at the bottom of the unit to protect the burner against drafts and for other purposes. As best shown in Figures 1 and 2, this pan 45 need extend only beneath the burner and can be of less width and length than the outer casing 10. One end

thereof is open to provide an air inlet opening 46. This pan is removably connected to the outer casing as indicated by the numerals 47 and 48.

Prior to installation of the floor furnace, the rough plumbing will have been installed, including a fuel-supply pipe 50 shown as extending through one of the members or joists 13 and being stubbed off immediately therebeyond. As the extremity of this fuel-supply pipe extends into the opening 12 which is to receive the floor furnace and as it is in the path of movement of an end wall 54 of the outer casing 10, it is desirable to provide an upright passageway 52 extending vertically along this end wall of the outer casing 10. This passageway is formed by a covered or uncovered vertical slot open at its lower end and extending upward a distance to accommodate the fuel-supply pipe during lowering of the casing. In the preferred embodiment, this passageway is formed, and the slot is covered, by a U-shaped structure 53 extending inwardly of the outer casing 10. This U-shaped structure 53 may be formed as a separate element connected to the end wall 54 of the outer casing 10, in which event it will, in effect, bridge the vertical slot of this end wall, or it may be formed integrally with the end wall 54, as by deforming same to provide the U-shaped structure 53 as a vertical channel to bound the outwardly-opening passageway 52. The lowermost end of the U-shaped structure 53 terminates at the bottom wall 11, as best shown in Figure 5, while the upper end, indicated by the numeral 55, terminates just below the fuel-supply pipe 50 when the furnace is in installed position. The upper end of the slot in the end wall 54 is above the upper end 55 of the U-shaped structure 53 to provide an opening 56 loosely receiving the end of the fuel-supply pipe. Thus, the stubbed-off pipe 50 does not interfere with the downward movement of the furnace during installation, and the upper end 55 of the U-shaped structure 53 terminates a sufficient distance below the pipe 50 to permit unscrewing any pipe cap previously thereon and substituting an elbow 57.

The fuel-control means of the furnace is preferably positioned sufficiently near the upper end of the outer casing 10 to be accessible through the open top thereof for connection, inspection, or repair. This fuel-control means may include a pressure regulator 60, a pilot-control valve 61, and a main or burner-control valve 62 best shown in Figures 3 and 4, or other fuel-control devices. The main valve 62 is shown as being manually controlled by insertion of a suitable key through the grill 16 to engage a stem 63 of the valve, but it should be clear that a thermostatically-controlled main valve may be substituted or employed in addition to the main valve. As illustrated, the pressure regulator 60 and the valves 61 and 62 are connected to the elbow 57 by a suitable coupling 58, preferably a flexible copper pipe secured to the elbow 57 and a nipple of the pressure regulator 60 by internally threaded hexagonal collars 64, or a suitable pipe union may be employed.

In the preferred embodiment of the invention, fuel-conducting pipe means extends downwardly from the fuel-control means at a position just inside one end of the outer casing 10, as best shown in Figures 1, 3, 4, and 5. This pipe means includes a main burner-supply pipe 65 extending downwardly through a pipe-conducting open-

ing 56 of the bottom wall 11 and thence inwardly to an air mixer 67 of the burner 35.

The fuel-conducting pipe means includes also a small pilot-supply pipe 68, usually formed of one-quarter inch copper tubing to be readily bent, this pipe extending through the pipe-conducting opening 66 and the lower end of the pipe providing a lower pilot-connected portion 69 to which a pilot 70 is connected. This pilot has the usual orificed head and is disposed to produce a burner-lighting flame in the combustion chamber. In this embodiment of the invention, the pilot or pilot flame enters the combustion chamber sideways through a pilot-receiving opening 72 separate from the burner-receiving opening, namely, the open lower end of the combustion chamber 33. The uppermost end of the pilot-supply 68 is removably connected to the pilot-control valve 61, preferably by use of a detachable fitting 73, for example a flared fitting in which a hexagonal collar threaded to the pilot-control valve 61 draws the pilot-supply pipe 68 against the valve. By use of this type of fitting, the entire pilot assembly (including the pilot-supply pipe 68, the pilot-connected portion 69, and the pilot 70), can be attached or detached from the pilot-control valve 61 merely by turning the hexagonal collar, thus permitting attachment or detachment of the pilot assembly without unscrewing the whole pilot assembly from the pilot-control valve. However, a screw-type fitting can be employed if desired. The amount of fuel supplied to the pilot is controlled by turning a valve stem 74, engageable by a key inserted through the grill 16.

The invention contemplates that the lower pilot-connected portion 69 be movable and, in this embodiment of the invention, sidewise movement thereof is possible by manual flexure of the upper portion of the pilot-supply pipe 68, even when connected to the valve 61 by the fitting 73, access being had through the open top of the outer casing 10. By manual flexure of the pilot-supply pipe 68 to move the lower end toward the end wall of the casing 10, the lower pilot-connected portion 69 can be made to swing outward, while substantially horizontally disposed, from its position shown in Figure 1. Alternatively, if the fitting 73 is disconnected, the lower pilot-connected portion 69 can be moved horizontally outward from the vicinity of the pilot-receiving opening 72, and the entire pilot assembly can be removed by access through the open top of the outer casing 10.

In addition, the preferred embodiment of the invention preferably provides a guide means for receiving the pilot 70 and the pilot-connected portion 69 to guide same into correct burner-lighting relationship, while at the same time facilitating the installation and removal of the pilot assembly as a whole. For this purpose, Figures 1 and 2 illustrate a pilot guide 75 providing a pilot-guiding passage 76 below the bottom wall 11. This pilot guide is preferably tubular and is shown in Figure 2 as comprising a U-shaped member secured to the bottom wall 11. In this embodiment, the outermost end of the pilot guide 75 terminates short of the pipe-conducting opening 66, preferably at the inner end of a pilot-receiving opening or slot 77, which opens on the pipe-conducting opening 66, as best shown in Figure 3. The pilot-receiving opening or slot 77 is preferably closed by a removable cover 78, mounted as will be later described. Generally stated, the outermost end of the pilot guide 75 should terminate short of the outer casing 10, preferably at a point,

usually below the inner casing 22, which will permit withdrawal of the pilot 70 and the pilot-connected portion 69 from the pilot guide in a manner to be hereinafter described.

It is usually desirable to enclose the fuel-conducting pipe means from the air circulating in the circulating-air passage 21. For this and other purposes, the invention provides a wall structure 80, preferably removable. In the preferred embodiment shown in Figures 1 to 5, this wall structure includes a U-shaped partition wall 81 forming a space 82 immediately inside an end wall of the outer casing 10. The side members of the partition wall 81 may be detachably connected to this end wall of the casing by any suitable means. For example, each side member may include an outwardly-bent tongue 83 vertically movable in a guide 84 secured to the casing, whereby the entire partition wall is vertically slidable from the casing 10 through the open top thereof. The lowermost end of the partition wall 81 rests flush against the bottom wall 11 at the periphery of the pipe-conducting opening 66, and the cover 78 for the pilot-receiving opening or slot 77 is preferably connected to the lower end of the partition wall so that this opening or slot is automatically closed off when the partition wall is lowered into the position shown in Figure 1. The uppermost end of the partition wall 81 preferably carries a cover 85 for closing the upper end of the space 82, this cover terminating flush with the inner surface of the end wall of the outer casing 10. An opening 86 (Figure 4) may be provided for snugly receiving the stem 63 of the main valve, and another opening 87 above the pilot-control valve 61 for receiving the stem 74 of the pilot valve. The width of the partition wall 81 between its side members is preferably, though not necessarily, less than the width of the outer casing 10, whereby this partition wall occupies only a portion of the circulating-air passage 21 at this end of the heating unit.

In installing the heating unit thus far described, the entire assembled unit is lowered in the opening 12, the outwardly-facing passageway 52 accommodating the stubbed-off fuel-supply pipe 50, as previously described. The partition wall 81 will be removed during installation and the pressure regulator 60, valves 61 and 62, and main burner-supply pipe 65 may be sequentially connected to the fuel-supply pipe 50. Alternatively and preferably, these elements may previously have been assembled and mounted securely in the outer casing 10, the complete pipe assembly being then connected to the elbow 57, after lowering the heating unit, by the flexible tubing connector or coupling 63. The pilot assembly can form a part of this pipe assembly, having previously been positioned in the pilot guide, or this pilot assembly may subsequently be lowered through the pipe-conducting opening 66 and the pilot-receiving slot 77 being then moved inwardly so that the pilot 70 is within the pilot guide 75, this guide insuring correct guidance into burner-lighting relationship. The uppermost end of the pilot-supply pipe 68 will then be connected by fitting 73 to the pilot-control valve 61. Any necessary adjustments of the fuel-control means are then made, after which the partition wall 81 is lowered into position.

In removing the pilot assembly for inspection or repairs, the partition wall 81 is first removed. The hand can then be inserted into the open top of the casing 10 and the pilot-supply pipe 68 deformed toward the outer casing 10, thus swing-

ing the pilot 70 out of the pilot guide 75. At this time, the pilot-supply pipe 68 can be further bent to bring the pilot toward the top of the outer casing while still connected to the pilot-control valve 61, this being possible in view of the flexible nature of the pipe 68. Inspection or repairs can be made and the pilot reinserted into the pilot guide 75. Alternatively, the coupling 73 can be disconnected and the pilot 70 swung outward and thence upward through the slot 77 or opening 66 for inspection or repairs.

In the alternative construction suggested in Figure 6, the pilot-receiving opening, indicated by 72a, is disposed above the bottom wall 11, as is also the pilot guide 75a. In this instance, this pilot guide is suitably secured to the outer wall of the combustion-chamber structure 20 to prevent any possibility of leakage of fuel or products of combustion into the circulating-air passage 21. In this embodiment, a pilot-receiving opening or slot 77a is formed in the lower end of the partition wall 81, and a removable cover 78a, preferably secured to the partition wall, encloses the pilot-supply piping from the circulating-air passage and preferably extends downwardly snugly around the pilot guide 75a. It will thus be apparent that the pilot guide can be above or below the bottom wall 11 of the heating unit.

The invention contemplates the employment of any means for inserting and removing the pilot assembly from the open top of the casing. An alternative construction, permitting hinged or lateral swinging of the pilot into and from its burner-lighting relationship, is shown in Figures 7 and 8. Here, the pilot-supply pipe 68 and the pilot-connected portion 69 are adapted to swing about a vertical axis in the space 82 and passing through the pilot-control valve 61. The pilot-connected portion 69 is bent inwardly so that the pilot 70 swings into and from an opening 100 in a side wall of the combustion-chamber structure 20, as best shown in Figure 7. The pilot may be guided by a flaring pilot guide 101 secured to the combustion-chamber structure. To remove the pilot structure of this embodiment of the invention, it is necessary only to loosen the fitting 73 and, by grasping the pilot-supply pipe 68, turn it into dotted line position 104 of Figure 7 for inspection. If repairs are desired, the fitting 73 is completely removed, whereupon the entire pilot structure can be drawn upward through the space 82.

It will be apparent that the pilot guide 75 or 101 facilitates correct insertion of the pilot which can enter such pilot guide at a position removed from the combustion chamber and be guided into and retained in correct burner-lighting position. It will be apparent, also, that all embodiments of the invention herein-suggested provide for movement of the pilot in a substantially horizontal direction toward and away from the combustion chamber by manual access through the open top of the outer casing 10. In fact, all of the elements of a heating unit likely to give trouble or difficult to service are positioned near, and insertable or removable from, the upper end of the casing, being accessible from the room and thus requiring no entry into the restricted space between the floor and the ground.

The embodiments of the invention herein-disclosed are merely exemplary. While I have chosen to illustrate the invention as applicable to a floor furnace, it should be apparent that it can be used also with floor-installed space heat-

ers or other heating units, in which, for example, the bottom wall 11 is eliminated and in which, for example, the partition 81 can sometimes be eliminated. It will be apparent, also, that various changes and modifications can be made without departing from the spirit of the invention as defined in the appended claims.

I claim as my invention:

1. In a heating unit for installation in the floor of a building, said floor being disposed a distance above the ground sufficient to receive the heating unit when lowered through an opening of the floor, said heating unit including in combination: an outer casing having an open top and adapted for suspension in said opening to be disposed below said floor; a combustion-chamber structure fixed within said outer casing and spaced therefrom to define a circulating-air passage, said combustion-chamber structure defining a combustion chamber; a burner for burning fuel in said combustion chamber; means for conducting products of combustion from said combustion chamber; fuel-control means disposed within said outer casing below floor level but near the upper end of said outer casing to be accessible through the open top of said casing, said burner being located below said fuel-control means; a fuel-conducting pipe extending downwardly from said fuel-control means to said burner; a pilot extending into said combustion chamber, said pilot being disposed below said fuel-control means; a pipe means including a pilot-connected portion extending to and communicating with said pilot to supply fuel thereto, said pipe means including an upwardly-extending portion; and wall means within the outer confines of said outer casing and providing an upright space separated by said wall means from said circulating-air passage, said pipe means extending downwardly in said upright space.

2. A combination as defined in claim 1, including a pilot-control valve within said outer casing near the upper end thereof to be accessible through the open top of said casing, and including means for detachably connecting said upwardly-extending portion of said pipe means to said pilot-control valve, said upwardly-extending portion being accessible through the open top of said outer casing to permit removal of said pipe means therethrough.

3. A combination as defined in claim 1 in which said fuel-control means is disposed in the upper end of said upright space and in which said fuel-conducting pipe extends downwardly in said space.

4. A combination as defined in claim 1 in which said wall means includes a partition wall and means for removably connecting same to said outer casing.

5. A combination as defined in claim 1 in which said wall means includes a partition wall having side portions, and including means for slidably connecting said side portions to said outer casing to permit said partition wall to be removed from said circulating-air passage.

6. In a heating unit for installation in the floor of a building, said floor being disposed a distance above the ground sufficient to receive the heating unit when lowered through an opening of the floor, said heating unit including in combination: an outer casing having an open top and adapted for suspension in said opening to be disposed below said floor, said outer casing providing a wall; a combustion-chamber structure within said outer casing and spaced there-

from to define a circulating-air passage, said combustion-chamber structure defining a combustion chamber; a burner for burning fuel in said combustion chamber; means for conducting products of combustion from said combustion chamber; a fuel-conducting pipe means providing an upper end adapted for connection to a source of fuel and extending downwardly inside said outer casing at a location spaced from said wall of such casing, said fuel-conducting pipe means supplying fuel to said burner; and a partition wall extending across said fuel-conducting pipe and having ends extending to said wall at opposite sides of said fuel-conducting pipe means to form a space separated by said partition wall from the air circulating in said circulating-air passage, the distance between said ends of said partition wall being less than the horizontal length of said first-named wall.

7. A combination as defined in claim 6, including means for detachably connecting said partition wall to said wall of said casing to permit removal of said partition wall by access through the open top of said casing to give access to said fuel-conducting pipe means.

8. In a heating unit for installation in the floor of a building, said floor being disposed a distance above the ground sufficient to receive the heating unit when lowered through an opening of the floor, said heating unit including in combination: an outer casing having an open top and adapted for suspension in said opening to be disposed below said floor, said outer casing having a lower wall providing an opening; a combustion-chamber structure extending upwardly from said opening of said lower wall and spaced from said outer casing to define a circulating-air passage; a burner disposed at least partially below said wall for burning fuel within said combustion-chamber structure; means for conducting products of combustion from said combustion-chamber structure; fuel-conducting pipe means extending downwardly within said outer casing, said lower wall providing a pipe-conducting opening through which said pipe means extends to said burner; and wall means extending from said pipe-conducting opening of said lower wall to a position above the upper end of said fuel-conducting pipe means providing a space for said pipe means, said wall means separating said space from air circulating in said circulating-air passage, said fuel-conducting pipe means extending downwardly in said space.

9. A combination as defined in claim 8, in which said pipe means includes a small pilot-supply pipe extending downward in said space and providing a lower portion extending sidewise toward said combustion chamber, and including a pilot carried by said lower portion, said lower wall providing a pilot-removing opening between said pipe-conducting opening and said combustion-chamber structure of sufficient size to pass said pilot and said lower portion of said pilot pipe, and including a removable cover for said pilot-receiving opening.

10. In a heating unit for installation in the floor of a building, said floor being disposed a distance above the ground sufficient to receive the heating unit when lowered through an opening of the floor, said heating unit including in combination: an outer casing having an open top and adapted for suspension in said opening from said floor; a combustion-chamber structure within said outer casing and spaced therefrom to define a circulating-air passage, said

combustion-chamber structure defining a combustion chamber and having a burner-receiving opening and a separate pilot-receiving opening disposed above the burner-receiving opening; a burner adjacent said burner-receiving opening; means for conducting products of combustion from said combustion chamber; a pilot extending substantially horizontally through said pilot-receiving opening; and means for mounting said pilot to swing into and from said pilot-receiving opening.

11. A combination as defined in claim 10, in which said burner-receiving opening is at the bottom of said combustion-chamber structure, and in which this structure provides a substantially vertical wall in which is formed said pilot-receiving opening.

12. In a heating unit for installation in the floor of a building, said floor being disposed a distance above the ground sufficient to receive the heating unit when lowered through an opening of the floor, said heating unit including in combination: an outer casing having an open top and adapted for suspension in said opening to be disposed below said floor; a combustion-chamber structure within said outer casing and spaced therefrom to define a circulating-air passage; a burner for burning fuel in said combustion-chamber structure; a partition wall mounted in said outer casing and cooperating therewith in defining a vertically-extending space substantially closed from communication with air moving in said circulating-air passage; a pilot valve in said space at a position to be manually accessible through said open top of said casing; a pilot assembly including a pilot and a pilot-supply pipe extending downward through said space and providing a pilot-carrying portion attached to said pilot, said pilot-carrying portion extending inwardly a sufficient distance to dispose said pilot in burner-lighting relationship; and means near said open top of said casing for detachably connecting said pilot-supply pipe to said pilot valve, said space being of sufficient horizontal dimension to permit removal of said pilot assembly by drawing same upward through said space after disconnection from said pilot valve.

13. In a heating unit for installation in the floor of a building, said floor being disposed a distance above the ground sufficient to receive the heating unit when lowered through an opening of the floor, said heating unit including in combination: an outer casing having an open top and adapted for suspension in said opening to be disposed below said floor; a combustion-chamber structure within said outer casing and spaced therefrom to define a circulating-air passage, said combustion-chamber structure defining a combustion chamber and providing a side wall having a pilot-receiving opening; a burner for burning fuel in said combustion chamber; means for conducting products of combustion from said combustion chamber; a pilot for producing a burner-lighting flame in said combustion chamber; and a movable pilot-supply pipe providing a downwardly-extending portion extending downwardly inside said outer casing from a point near the top of said casing and manually movable by access through the open top thereof, said pilot-supply pipe also providing a lower pilot-connected portion extending sidewise from said downwardly-extending portion and carrying said pilot in position to swing substantially horizontally into and from said pilot-receiving opening.

11

when the upper end of said downwardly-extending portion is moved.

14. A combination as defined in claim 13, including guide means adjacent said combustion-chamber structure and communicating with said pilot-receiving opening for guiding said pilot toward and away from said pilot-receiving opening when swinging into and from said opening.

15. In a heating unit for installation in the floor of a building, said floor being disposed a distance above the ground sufficient to receive the heating unit when lowered through an opening of the floor, said heating unit including in combination: an outer casing having an open top and adapted for suspension in said opening to be disposed below said floor; a combustion-chamber structure within said outer casing and spaced therefrom to define a circulating-air passage, said combustion-chamber structure defining a combustion chamber; a burner for burning fuel in said combustion chamber; means for conducting products of combustion from said combustion chamber; a pilot for producing a burner-lighting flame in said combustion chamber; a pilot-supply pipe extending downwardly inside said outer casing from a point near the top of said casing and accessible through the open top thereof, said pilot-supply pipe providing a lower pilot-connected portion extending sidewise to said pilot; and walls defining a pilot-guiding passage extending away from said combustion-chamber structure to receive said pilot and said lower pilot-connected portion and guide said pilot into and from said combustion chamber, said lower pilot-connected portion being displaceable substantially horizontally to withdraw said pilot from said combustion chamber through said pilot-guiding passage by manual movement of the downwardly-extending portion of said pilot-supply pipe.

16. A combination as defined in claim 15, including a covering wall removably attached to said casing and providing a space in which said pilot-supply pipe extends downward, said covering wall separating said space from the air circulating in said circulating-air passage, and in which said pilot-guiding passage extends toward and terminates short of said covering wall a sufficient distance to permit said pilot-connected portion to move clear of said pilot-guiding passage and be disposed in the remaining space between the end of said passage and said casing to be movable from the zone of the pilot-guiding passage when said covering wall is removed.

17. A combination as defined in claim 15, in which said casing provides a bottom wall, said pilot-guiding passage being adjacent said wall.

18. A combination as defined in claim 15, including a covering wall removably attached to said casing and providing a space in which said pilot-supply pipe extends downward, said covering wall separating said space from the air circulating in said circulating-air passage, and in which said casing provides a bottom wall, said pilot-guiding passage being adjacent said wall, and in which said pilot-guiding passage extends toward and terminates short of said covering wall, said bottom wall providing an opening extending from the end of said pilot-guiding passage and opening on the interior of said space provided by said covering wall, said opening providing space for the vertical passage for said pilot-connected portion of said pilot-supply pipe when withdrawn from said pilot-guiding passage.

19. In a heating unit for installation in the

12

floor of a building, said floor being disposed a distance above the ground sufficient to receive the heating unit when lowered through an opening of the floor, there being a fuel-supply pipe extending inwardly a short distance into the zone through which said heating unit moves during lowering into installed position, said heating unit including in combination: an outer casing having an open top and being of such size as to be lowered through the opening of said floor, said outer casing providing a wall having an outwardly-facing substantially vertical passageway to receive the inwardly-extending portion of said fuel-supply pipe during installation of said outer casing; a combustion-chamber structure within said outer casing; a burner for burning fuel in said combustion-chamber structure; and pipe means extending upward from said burner to be connectible with said fuel-supply pipe.

20. In a heating unit for installation in the floor of a building, said floor being disposed a distance above the ground sufficient to receive the heating unit when lowered through an opening of the floor, there being a fuel-supply pipe extending inwardly a short distance into the zone through which said heating unit moves during lowering into installed position, said heating unit including in combination: an outer casing having an open top and being of such size as to be lowered through the opening of said floor, said outer casing including an upright wall having a vertical slot providing an open portion adapted to receive the inwardly-extending portion of said fuel-supply pipe when said casing is in installed position, said slot providing space for said inwardly-extending portion of said fuel-supply pipe during installation of said outer casing; a combustion-chamber structure within said outer casing; a burner for burning fuel in said combustion-chamber structure; and pipe means extending upward from said burner to be connectible with said fuel-supply pipe.

21. In a heating unit for installation in the floor of a building, said floor being disposed a distance above the ground sufficient to receive the heating unit when lowered through an opening of the floor, said heating unit including in combination: an outer casing having an open top and adapted for suspension in said opening to be disposed below said floor; a combustion-chamber structure mounted within said outer casing and spaced therefrom to define a circulating-air passage, said combustion-chamber structure providing a combustion chamber; a burner for burning fuel in said combustion chamber; means for conducting products of combustion from said combustion chamber; a pilot fitting near the upper end of said outer casing; walls extending downwardly and inwardly to said combustion chamber and defining a passageway substantially closed at its sides from communication with the air in said circulating-air passage, the upper and lower ends of said passageway being disposed respectively adjacent said pilot fitting and said combustion chamber; a pilot structure including a small pilot-supply pipe and a pilot connected thereto; and means for removably mounting said pilot structure within said passageway in position to dispose said pilot in communication with said combustion chamber, said means including means for detachably connecting said pilot-supply pipe to said pilot fitting to permit upward withdrawal of the pilot structure from the heating unit without removal of the

13

combustion-chamber structure from said outer casing.

22. In a heating unit for installation in the floor of a building, said floor being disposed a distance above the ground sufficient to receive the heating unit when lowered through an opening of the floor, there being a fuel-supply pipe immediately beneath said floor, said heating unit including in combination: an outer casing having an open top and being of such size as to be lowered through the opening of said floor; a combustion-chamber structure secured within said outer casing and spaced therefrom to define a circulating-air passage, said combustion-chamber structure providing a combustion chamber; a partition wall within said outer casing and providing sides extending to said outer casing and an intermediate portion spaced from said outer casing to define a space having an upper end adjacent said fuel-supply pipe and a lower end horizontally opposite a portion of said combustion chamber; means for removably mount-

14

ing said partition wall within said outer casing, said means including inter-engaging means on said outer casing and said sides of said partition wall; and fuel-conducting piping connectable to said fuel-supply pipe and extending downwardly in said space to supply fuel to said combustion chamber.

JAMES STANLEY JOHNSON.
